BEATING IMPLEMENT

Filed June 23, 1930

Inventor

RAY V. SOWERS

By Thomas D. Ryan

Attorney

UNITED STATES PATENT OFFICE

RAY V. SOWERS, OF MUNCIE, INDIANA

BEATING IMPLEMENT

Application filed June 23, 1930. Serial No. 463,287.

This invention relates to improvements in implements for the agitating and beating of liquid masses. It has reference especially to devices of this kind intended for the beating and whipping of eggs, culinary solutions, and the like, and in which said devices are employed rotatable beaters or agitators and suitable gearing for imparting motion thereto.

Advantages desired are that the use of one hand only may be involved in operating the implement, and that the agitating element may be operable within a relatively small space and near the bottom of the utensil in which the solution is contained. These general advantages as well as certain more specific benefits hereinafter mentioned, are accomplished by and my invention is embodied in the new construction, combination and arrangement of parts described in the following specification and illustrated in the accompanying drawings. The invention is defined in the appended claims.

The several parts of the invention are identified by suitable characters of reference applied to them in the drawings in which—

Figure 1 is a front view of my improved beating implement.

Figure 2 is a side view taken in the direction of arrow 2 in Figure 1.

Figure 3 is a sectional plan view taken on the line 3—3 in Figure 1.

Figure 4 is a sectional plan view taken on the line 4—4 in Figure 1.

My improved implement as illustrated herein, is about eleven inches in length and may be designated as an egg beater. It will be understood however, that the device may be used for all general purposes for which an implement of this kind may be suitable, and also that it may be made up in various sizes, and in modified formation as to general structure and details.

The invention consists of a light sheet metal frame comprising opposed side members, the said frame having a finger hold at its upper portion, a rack retained slidably in and having a shank to extend above the frame, a palm hold on said shank, a spring between the frame and the palm hold to urge

the latter upwardly, a shaft having its lower end journaled in the bottom portion of the frame, and to which said shaft or beater element is secured, opposed spaced crown gear wheels secured to the shaft, a pillow block 55 retained slidably on the frame, a cross shaft journaled in the pillow block, a pinion on the cross shaft to mesh with the rack, and a gear wheel secured to the cross shaft, whose diameter is such that when it is in mesh with one of the crown gear wheels it is out of mesh with the other crown gear wheel.

The frame consists of a light flat metal bar about one-half inch wide, bent to form to have the sides 1 and 2, the arms 3 and 4 and the foot portion 5. The extreme upper portions of the sides 1 and 2 have their edges bent inwardly to constitute a guide way neck 6, the function of which will be presently referred to. Projecting laterally from the upper end of said neck are the finger holds 7 and 7. Retained slidably in the guideway neck 6 is a rack bar 10 at whose upper end is provided a palm-hold member 11. This member 11 is of form and size to be conveniently engaged by the palm portion of the user's hand. 12 designates a coil spring reposed on the shank portion of the rack bar 10 and which is operable to urge the palm hold and rack upwardly. A slender shaft 13 has its upper end journaled in the top portion 14, and its bottom end journaled in the foot portion 5 of the frame.

The beater element may consist of a hub 14 having spaced radially disposed wire bow 85 shaped members stayed by an annular band 17, and which have the beater portions 15 and the curved portions 16. Deflector plates 18 and 18 may be secured to the arm members 3 and 4 at the desired height with relation to the beater element.

At spaced locations on the upper portion of the shaft 13, crown gear wheels 20 and 21 are secured, in opposed relation as shown in Figure 1. Between the sides 1 and 2 of the frame, I provide a pillow block 22. This pillow block is made of sheet metal bent to the formation in plan as shown in Figure 3, and it has the sides 22, in which a cross shaft 23 is journaled. The head portion 22a has

bearing against the inner face of the side 1 of the frame, and it constitutes a guideway for the rack 10a which is formed integral with the rack bar 10. The said head portion 22a also serves as a retainer for a pinion 24, which is secured on the cross shaft 23. The base portion 22b of the pillow block is of elongated formation, and it is provided with longitudinal slots 22c. Headed studs 26, which are riveted to the side 2 of the frame, are of a height to provide a clearance between the base portion of the pillow block and the side 2 of the frame. The pillow block is thereby movable freely, longitudinally of the frame. Secured on the said cross shaft is a relatively large gear wheel, which I designate as the drive gear wheel 25. The distance between the crown gear wheel, with relation to the measure of the diameter of the 10 said drive gear wheel 25 is such, that the drive gear wheel is in mesh with one only of the crown gear wheels. The studs 26 are positioned to so limit the distance of the upward travel of the pillow block (under the 15 urge of the spring 12) that there is the desired shallow meshing of the gear wheel 25 with the crown gear wheel 20, and a clearance of the crown gear wheel 21. The energy required for rotating the drive gear 20 wheel being greater than the energy required for the raising or lowering of same, the rotative movement of pinion 24 at the beginning of each stroke of the rack is negligible, the pinion therefore acting substantially in 25 the manner of a cross head.

It is obvious that with a lowering of the rack there is the rotating and the lowering of the gear wheel 25 to mesh with the lower crown gear wheel 21, and the rotative movement of the latter. Similarly, with the raising of the gear wheel 25 and the rotative movement thereof in a reverse direction, there is the rotative movement of the upper crown gear wheel 20.

45 In practicing the invention, the forefingers of the hand are engaged on the underside of the finger holds 7 and 7, the palm being in engagement with the palm hold 11. By a natural grasping or constricting, and then releasing, movement of the hand, the finger holds 7 and the palm hold 11 are drawn toward, and thence spring apart from, each other. On the downward stroke of the rack and by which there is a lowering of the pillow block and the drive gear wheel 25, and a rotative movement of said gear wheel in the direction of arrow 21a, the shaft 13, through crown gear 21, is moved rotatively in the direction of arrow 21b. Upon the upward stroke of the rack, and by which there is a raising of the pillow block and the drive gear wheel 25, and a rotative movement of the drive gear wheel in the direction of arrow 21c, the shaft 13, through crown gear 20, is moved rotatively in the same direction as

before, namely in the direction of arrow 21b. The velocity of movement of the shaft 13 may be varied by the user, according to the uses to which the device is applied. A minimum amount of time is required to obtain a 70 complete and effective agitation, mixing and whipping of the material being operated upon.

The user, by reason of using one hand only in operating the device, has the other hand 75 free. Thus it is practicable to add certain elements into the solution, without the necessity of halting the operation of the beater.

The invention is capable of being manufactured economically and is light in weight, 80 strong and durable, and is not liable to get out of order or repair. It requires no lubricating, and is capable of being easily and thoroughly cleansed.

Whereas I have shown my improved beating implement in the form of embodiment deemed preferable, it is understood that modifications may be made throughout in the structural features of the invention, within the scope of the appended claims, without departing from the spirit of my invention or sacrificing any of its advantages.

What I claim as my invention and desire to secure by Letters Patents is—

1. An implement of the kind described, comprising an upright metal frame having a finger hold at its upper portion, a rack retained slidably in the frame and having a shank to extend above the finger hold, a palm hold on said shank, a spring between the frame and the palm hold to urge the latter upwardly, a shaft having its lower end journaled in the bottom portion of the frame, spaced crown gear wheels secured to the shaft, a pillow block retained slidably on the frame, studs to limit the distance of movement of the pillow block, a cross shaft journaled in the pillow block, a pinion secured to the cross shaft and which meshes with the said rack, and a drive wheel secured on the cross shaft.

2. An implement of the kind described, comprising an upright metal frame having a guideway and finger hold at its upper portion, a rack retained slidably in said guideway and having a shank to extend above the finger hold, a palm hold on said shank, a pillow block retained slidably on the frame, a cross shaft journaled in the pillow block, a pinion secured to the cross shaft which meshes with the said rack, a drive gear wheel secured to said cross shaft, a shaft mounted in said frame for rotative movement, opposed crown gear wheels secured on said shaft at a spaced distance apart, greater than the measure of the diameter of the said drive gear wheel, a spring to urge the pillow block toward, and to cause the drive gear wheel to mesh with one of the crown gear wheels, and studs carried by the frame to limit the dis-

tance through which the said pillow block may move.

3. A manual device for converting reciprocative motion into rotary motion, comprising a frame having opposed sides, and being provided with a finger hold at one end, a rack retained slidingly in and having a shank to extend beyond said frame, there being a palm hold secured on said shank, a pillow block retained slidingly on the frame, a gear set journaled in the pillow block and consisting of a drive gear wheel, and a pinion gear wheel, the latter to mesh with the said rack, a shaft mounted in the frame for rotative movement, opposed gear wheels secured on said shaft at a spaced distance apart, greater than the measure of the diameter of the drive gear wheel, a spring to urge the pillow block toward, and to cause the drive wheel to mesh with one of said spaced gear wheels, and studs carried by the frame to limit the distance through which the said pillow block may move.
